UNITED STATES PATENT OFFICE.

HERBERT R. LAND, OF LITTLE ROCK, ARKANSAS.

LAMP-SOCKET LOCK.

1,226,338.

Specification of Letters Patent.

Patented May 15, 1917.

Application filed January 11, 1917. Serial No. 141,819.

To all whom it may concern:

Be it known that I, HERBERT R. LAND, residing at Little Rock, in the county of Pulaski and State of Arkansas, have invented a new and Improved Lamp-Socket Lock, of which the following is a specification.

My invention has reference to means for locking electric light lamps that is especially 10 designed for securely holding the lamp in its socket against working loose and partially or wholly breaking the light circuit and also to prevent the lamp from being stolen.

15 My invention has for its object to provide a device of the character stated of a simple and economical construction, in which is included a screw pin having a pointed end adapted for being forced against the metal 20 neck on the lamp globe and in such manner that the lamp cannot be readily unscrewed from the socket or work loose under ordinary conditions.

Another purpose of my invention is to 25 provide a lamp socket lock that may be readily applied to the conventional forms of lamp sockets and which leaves no projection or other external formation on the socket 30 that might interfere with the ordinary manner of cleaning the socket or the lamp and the use of shades on the globe.

My invention is a lamp socket lock that embodies the peculiar features of construction and novel arrangement of the parts 35 that will be hereinafter described, specifically pointed out in the appended claims and illustrated in the accompanying drawing, in which:

Figure 1 is a perspective view of an incandescent lamp with an attached socket 40 provided with my improved socket lock.

Fig. 2 is a vertical section of the lamp and the socket connection and the socket lock, the latter being adjusted for holding the 45 lamp from being freely unscrewed from the socket.

Fig. 3 is a similar view that illustrates the lock device adjusted to permit of the free removal of the lamp, and

50 Fig. 4 is a perspective view of the several parts that constitute my invention, the said parts being shown separated.

In the practical showing of my invention, 1 designates an ordinary incandescent lamp 55 and 2 the conventional type of socket which

includes the internal screw threaded liner 3 and the insulating sleeve 4.

My device includes a ring or sleeve 5 of suitable insulating material, preferably hard rubber, and of a length equal the length of 60 an aperture 6 that is drilled through the insulating sleeve 4 and the outer metal socket shell 7.

8 designates a short tubular hub that snugly fits within the sleeve 5 and which, in 65 practice, is formed by cutting down an ordinary wood screw, the head of which forms a flange bearing that seats against the inner side of the insulating sleeve 4 when the said plug or hub 8 is fit in the aperture 6 and 70 to thereby hold the device from working out through the said apertures 6.

The hub 8 is formed with an internal thread 80, provided for receiving a screw pin 9, the inner end of which is turned down 75 to form a sharp penetrating point 82 and the outer end of which is formed with a squared key receiving tap 81, the head of which, when the parts are operatively assembled, lies back of the outer end of the 80 hub 8, the latter, when the parts are applied, being flush with the outer surface of the socket shell, see Fig. 2.

By reason of forming the screw pin and the threaded hub in the manner shown, the 85 said hub, which fills the aperture 6 through the socket and shell and the sleeve 4, is held from working inwardly and loose by the threaded liner with which the head 83 of the said hub 8 engages, as is shown in the 90 said Fig. 2, by reference to which, it will be also observed that the liner 3 has an aperture 60 which alines the aperture 6 and provides for projecting the pointed end 82 of the screw pin up against the threaded rim 95 of the lamp bulb, it being understood that as the pin 9 is screwed home by applying a suitable implement to its tap 81, the sharp point 82 will become sufficiently indented in the said lamp bulb rim to hold the lamp 100 securely locked against being unscrewed or becoming loosened under ordinary usage.

From the foregoing taken in connection with the drawing, the complete construction, the manner of the application thereof 105 and the advantages of my invention will be readily apparent to those skilled in the art to which it appertains.

In applying my socket lock device to the conventional forms of lamp sockets, it is 110

only necessary to provide an aperture 60 in the liner that is sufficiently large to permit slipping the complete article from inside the socket with the insulating sleeve 5 and the attached parts projected through an aperture 6 drilled in the socket shell, the insulating sleeve being made fast to the shell in any suitable manner.

What I claim is:

- 10 1. In combination with an incandescent lamp and socket or holder therefor; of an insulating sleeve mounted in the socket shell with its outer end flush with the outer surface of the said shell, a metallic hub 15 fixedly held in the sleeve and including a head portion at the inner end that extends over the inner end of the insulating sleeve, the said hub having a threaded bore, a screw pin that engages the said bore, said pin having its inner end shaped for interlockably 20 engaging the metal end rim of the lamp when the pin is screwed home, the outer end of the pin being shaped for receiving a suitable turning implement.
- 25 2. The combination with an incandescent

lamp and a socket or holder therefor, the latter including a threaded liner and an insulating sleeve that is located between the liner and the socket shell, the said sleeve and the socket shell having alining apertures, 30 the liner having an aperture of larger diameter than the apertures in the sleeve and shell; of a locking device consisting of an insulator sleeve and tubular hub that passes through and is fixedly attached to the sleeve 35 and which includes an annularly enlarged head portion at the inner end, the said insulator sleeve being adapted for tightly fitting in the apertures in the socket shell and the socket insulating sleeve, the said device 40 being insertible through the aperture in the socket liner, the said hub having an internal bore and a screw pin engaging the said screw threaded bore, the said pin having a sharp penetrating point for engaging the 45 metal threaded end of the lamp and a metal threaded end of the lamp and a headed portion for receiving a suitable turning tool.

HERBERT R. LAND.
